ORTHOPEDIC BRACE FOR THE BACK

Randall H. Hale, Northridge, Calif.

Application May 22, 1958, Serial No. 51,012

Term of patent 14 years

(Cl. D83—1)

Fig. 1

Fig. 2

Fig. 3

Fig. 1 is a left front perspective view of an orthopedic brace for the back, embodying my new design;

Fig. 2 is a left rear perspective view of the same; and
Fig. 3 is a bottom plan view of the same.

I claim:

The ornamental design for an orthopedic brace for the back, as shown.
